CLAIM

The ornamental design for an eight-lens camera, as shown and described.

DESCRIPTION

FIG. 1 is a bottom and front perspective view of an eight-lens camera showing our new design;

FIG. 2 is a top and back perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is an enlarged scale top plan view thereof; and,

FIG. 8 is an enlarged scale bottom plan view thereof.

The broken lines depict portions of the eight-lens camera in which the design is embodied that form no part of the claimed design.
